COMBINED SHOWER AND DISPENSING FIXTURE

Karl R. Stuckey, 1222 E. Dianna,
Phoenix, Ariz. 85020

Filed Aug. 29, 1966, Ser. No. 3,613

Term of patent 14 years

(Cl. D23—3)

FIG. 2

FIG. 1 is a front perspective view of a combined shower and dispensing fixture showing my new design; and
FIG. 2 is a rear perspective view thereof.

I claim:

The ornamental design for a combined shower and dispensing fixture, substantially as shown.
